UNITED STATES PATENT OFFICE

152,503

DESIGN FOR AN ADJUSTABLE BELT

Harry Stelzer, New York, N. Y.

Application November 13, 1947, Serial No. 142,512

Term of patent 14 years

(Cl. D3—10)

To all whom it may concern:

Be it known that I, Harry Stelzer, a citizen of the United States of America, residing in New York, county of New York, and State of New York, have invented a new, original, and ornamental Design for an Adjustable Belt, of which the following is a specification, reference being had to the accompanying drawing, forming part thereof.

Fig. 1 is a front perspective view of an adjustable belt, showing my new design.

Fig. 2 is a front perspective view of the link portion in open position.

The rear view of Fig. 1 is substantially the same as that shown in the drawing.

I claim:

The ornamental design for an adjustable belt, substantially as shown and described.

HARRY STELZER.
